UNITED STATES PATENT OFFICE.

HENRY W. BLAIR, OF MANCHESTER, NEW HAMPSHIRE.

MEANS FOR DIMINISHING, DEADENING, AND PREVENTING SOUND.

SPECIFICATION forming part of Letters Patent No. 740,081, dated September 29, 1903.

Application filed September 29, 1896. Renewed March 7, 1903. Serial No. 146,757. (No model.)

To all whom it may concern:

Be it known that I, HENRY W. BLAIR, a citizen of the United States, residing at Manchester, in the county of Hillsboro and State 5 of New Hampshire, have invented certain new and useful Improvements in Methods and Means for Diminishing, Deadening, and Preventing Sound and the Cause Thereof and for other Purposes; and I do hereby declare 10 the following to be a full, clear, and exact description of the invention, such as will enable others skilled in the art to which it appertains to make and use the same.

My invention relates to improvements in 15 the methods and means for diminishing, deadening, and preventing sound, especially of machinery and for other purposes. In the present instance it is shown as applied to electric street-car motors merely for the purpose of showing one way in which it may be 20 usefully employed.

I attain the foregoing results, as far as electric cars are concerned, by the devices illustrated in the accompanying drawings, in 25 which—

Figure 1 is a longitudinal vertical section on line $\alpha\alpha$, Fig. 2. Fig. 2 is a top plan view of a portion of the running-gear, showing my improvements, the trucks and axle-boxes being omitted. This figure also shows an envelop and connected air-pump operated by an eccentric carried on the same axle as bears the machinery.

Similar letters refer to similar parts throughout both views.

The letter A represents the body of an electric car having any suitable construction of motor-gearing. Surrounding the motor is an envelop or covering B, having, if desired, 30 a lining i of lead or other substance which is a non-conductor of sound. If desired, there may be several envelops having air-chambers between them, from which the air may be partially or substantially wholly exhausted.

C is a valve to which an air-pump may be attached for the purpose of exhausting the air from the envelop or envelops B by hand, or the air may be exhausted by an automatic air-pump D and D', connected to the axle E, 45 to which is secured an eccentric F and F', or by the use of explosives, or by the conden-

sation of gases or any other means which may be devised. When the car is in motion, the pump is operated and the air exhausted from the covering B. Any of the well-known 55 means may be used for throwing the gearing of the air-pump out of operative condition and restore the same to operative condition. The covering B has a door g , (shown in dotted lines, Fig. 2,) through which access may be 60 had to inspect the motor whenever desired. The door g is provided with air-cushions f , so that when closed it will fit snugly and be substantially air-tight.

The electric current enters through an insulated hole o in the usual way. It will be noticed that the covering B, which incloses the armature r , commutator s , field-magnets u , and other parts connected to the electric motor proper, which cause the unpleasant 70 sound so often heard when in operation, also protects the machine from dirt, dust, or accidental injury. By the exhaustion of the air from the envelop or envelops B no sound-waves can proceed therefrom. There may be 75 a stuffing-box v where the envelop surrounds the axle E to prevent the ingress of air; but any other means may be employed for the same purpose. The covering B may be secured to or supported by the car or truck or 80 axle in any suitable manner.

I do not confine the application of my invention to street-cars actuated by electricity, for it may be readily applied to various forms of machinery to prevent friction, economize 85 motive power, secure regularity of motion and the economy of lubricants necessary to the moving and actuating parts—such, for instance, as type-writers and time-measurers. In fact, my invention is of general application, and therefore I do not limit it to any special form of construction.

Having thus described my invention, what I claim is—

1. A casing inclosing machinery and means to exhaust the air therefrom operated by the inclosed machinery, substantially as set forth.
2. An envelop covering machinery and carrying an air-pump, and an eccentric connected with said pump and operated by an axle 100 driven by said machinery.
3. An envelop covering machinery and car-

rying an air-pump to exhaust the air from said envelop in combination with an axle carrying said devices.

4. An envelop covering machinery and carrying an air-pump to exhaust the air from said envelop in combination with an axle of a car carrying said devices and actuating means for operating said pump.

5. An envelop covering machinery carried by an axle, an air-pump and means driven by the axle for operating the pump to exhaust the air from the same, as set forth.

6. An envelop covering machinery and carrying an air-pump, in combination with a car-

axle carrying said devices, an eccentric for 15 exhausting the air from the envelop operated by the car-axle.

7. The combination of the axle of a car, an envelop covering machinery on said axle and carrying an air-pump, and means operated 20 by said axle to work the pump.

In testimony whereof I affix my signature in presence of two witnesses.

HENRY W. BLAIR.
